UNITED STATES PATENT OFFICE

LEE W. HOVEY, OF CHICAGO, ILLINOIS

BULLETIN FRAME

Application filed January 25, 1928. Serial No. 249,311.

This invention relates to a frame, and more particularly to a bulletin frame, and the object of this invention is to provide such a frame which is adapted to be readily disassembled for the purpose of inserting bulletins, when desired, and adapted to be readily assembled and locked in assembled position.

Another object of my invention is to provide such a device comprising a plurality of opposed metallic channel members having means on the ends thereof for detachably securing each member to the adjacent members and also being provided with extensions 15 on the side portions of the channel members adapted to engage and firmly urge against sheets of glass or other suitable material which may be positioned therebetween and between which the bulletins are normally 20 positioned.

My invention will be best understood by reference to the accompanying drawings forming a part of this specification and in which:

25 Figure 1 is a front elevational view of a bulletin frame incorporating my invention.

Figure 2 is an end elevational view of that shown in Figure 1.

Figure 3 is a sectional view taken on line 30 3—3 of Figure 1.

Figure 4 is a perspective view of the bottom channel member comprising a portion of the frame.

Figure 5 is a perspective view of the channel member shown on the right side of Figure 1.

For the purpose of illustration, I have shown the preferred form of my invention in the drawings, and which comprises a plurality of channel members 5 consisting of a bottom portion 6, side portions 7, and extensions 8 on the side portions.

As best shown in Figure 3 the extensions 8 are concave on the outside thereby pressing 45 a convex inner surface in engagement with the sheets of glass or similar material 9, and urging against the same for holding them in place. The members 5 are preferably made of sheet material pressed or died into form, 50 and therefore possess the desired amount of

flexibility for constantly exerting a sufficient spring pressure on the glass plates 9, as heretofore stated. Between the sheets of glass is positioned a cushioning felt or similar material 10, on which the bulletins 11 and 12 55 are positioned. It will be apparent that it is not necessary to use thumb tacks or any other securing means for holding the bulletins in place, since they are pressed on to the surface of the felt by means of the pressure exerted upon the glass plates by the extensions 8.

The channeled members 5 are provided with a tapered extension 13 on one end, the extremity of which is formed into an arc of 60 a circle as shown at 14. Adjacent the opposite end of the channel members is provided a strap 15 died integral with the bottom portion 6 and being of sufficient size to receive the extremity 14 of an adjacent channel member therethrough, as shown in the assembled 65 illustration in Figure 1.

Two of the channeled members are of a slightly different construction than the others on one end thereof for the purpose of adapting the same to receive a locking means. This difference consists of an extension 16 70 on the right hand end of the bottom member which is provided with an opening 17, adapted to receive the strap 18 which is died in the same manner as the strap 15, but is formed longitudinally of the body portion instead of transversely. The members 13 and 16 extend at right angles to the bottom portion 6 for the purpose of engaging the bottom portions 75 of the adjacent members which in this frame form a rectangle, however, it is within the scope of this invention to arrange said portions 16 and 13 at any other desired angle, for accommodating other shapes of frames. 80 A padlock 18' may be used to secure the portions 16 and 18 together as shown in Figure 1, and when it is desired to disassemble the frame, it is only necessary to remove the padlock, lower the bottom member into the position shown in dotted outline, and the other members may then be removed by withdrawing each member with its strap 15 off of the curved portion 14 of the extensions 13, as 85 shown, and for assembling the frame, the

90

100

reverse operation is followed, suitable ears 19 are secured to the top member by means of rivets 20 for supporting the frame on suitable hangers as may be desired.

Having described my invention in its preferred form of construction, it will be apparent to those skilled in the art that it is capable of variations without departing from the spirit of the invention, and I do not wish to be limited to the exact details herein illustrated and described, but desire to avail myself of such variations and modifications as come within the scope of the appended claims.

I claim as my invention:

1. A frame comprising a plurality of opposed metallic channel members; said members consisting of a bottom portion and side portions; extensions on the side portions of said channel members engaging sheets of glass positioned therebetween; means projecting from the bottom portion on each end of said channel members for detachably securing said members together; one of said securing means adapted to receive locking means therethrough for locking the entire frame as a unit.

2. A frame comprising a plurality of opposed metallic channel members; said members consisting of side and bottom portions; means integrally formed with the respective bottom portions adjacent the ends thereof and arranged to interlock and detachably secure the members from disassembly; extensions on the side portions of said channel members having a convex inner surface yieldingly urging against sheet members positioned therebetween for holding said sheet members centrally in said channels; and cushioning means between said sheet members arranged to secure display cards in position.

40 In testimony whereof I have signed my name to this specification.

LEE W. HOVEY.
